UNITED STATES PATENT OFFICE.

ARTHUR J. MORSE, OF SALISBURY, CONNECTICUT, ASSIGNOR TO THE MORSE-KEEFER CYCLE SUPPLY COMPANY, OF SAME PLACE.

TRIMMING AND DRILLING MACHINE.

SPECIFICATION forming part of Letters Patent No. 601,379, dated March 29, 1898.

Application filed August 10, 1897. Serial No. 647,747. (No model.)

To all whom it may concern:

Be it known that I, ARTHUR J. MORSE, of Salisbury, in the county of Litchfield, in the State of Connecticut, have invented new and useful Improvements in Trimming and Drilling Machines, of which the following, taken in connection with the accompanying drawings, is a full, clear, and exact description.

My invention relates to machines for trimming the ends and drilling nipples for bicycle-spokes or analogous or similar devices; and the object is to provide a machine that will operate on several nipples or other articles simultaneously, producing a somewhat different operation on each, and that will operate upon a series of nipples successively.

To this end my invention consists in the combination, in a nipple-finishing machine, of a disk provided with chambers to hold the nipples, means to rotate the disk intermittently, a longitudinally-movable bar, the driving-shaft, a cam-wheel on the driving-shaft to move the bar, a spindle adapted to be reciprocated in bearings by the said bar, a chuck on the end of the spindle to hold a tool to operate upon the nipples, and a pulley on the spindle for rotating the same; and my invention consists in certain other combinations of parts, hereinafter described, and specifically set forth in the claims.

In the drawings hereto annexed and forming a part of this specification, Figure 1 is a top plan view of my invention. Fig. 2 is a front side elevation. Fig. 3 is the rear side elevation. Fig. 4 is an end elevation looking from right to left of Fig. 1. Fig. 5 is the same end view of some of the important movable parts shown in their operative position or the reverse of that indicated in Fig. 4. Fig. 6 is an end view of the machine, looking from left to right of Figs. 1 and 2. Figs. 7 to 9, inclusive, show different views of the trimming-chuck. Fig. 10 shows an end and side view of the trimming knife or cutter, and Figs. 11 and 12 show side and sectional views of a nipple.

Referring specifically to the drawings, A is the frame of the machine, having forward extensions *a* and *a'* for the pair of spindles B and C to turn in, and rearward extensions *b* and *b'* for the driving-shaft D to turn in. The spindles B

and C are parallel with each other and lie with their axes in the same horizontal plane.

The driving-shaft D carries a pair of cam-wheels D' and D'', the cam-surface of each being on one side of the rim and on the sides facing each other. These cam-wheels operate upon a pair of longitudinally-movable bars E' and E'', sliding in a guideway E, arranged on the top of the frame A, parallel with the driving-shaft D, through a pair of small rollers d' and d'', turning on one side of the sliding bars. The right-hand end of bar E' slides in another bearing on the frame.

The sliding bars E' and E'' are in line with each other and are carried toward each other by the cam-wheels simultaneously, as hereinafter explained. The bar E' is connected by a forwardly and horizontally extending bar F with the right-hand ends of the spindles B and C to reciprocate them in their bearings while they are being rotated by continuously-running belts (not shown) on their pulleys B' and C'. The sliding bar E' and the spindles B and C are threaded where they pass through the bar F, so that nuts f' f' and f' f' on said bars and spindles on opposite sides of the bar F may properly adjust the bar F. The nuts f' f' do not bind on the sides of the bar F, but are separated sufficiently to allow the spindles B and C to rotate. The left-hand ends of the spindles are shown provided one with a trimmer-chuck c and the other with a drill-chuck c', so that both operations may be effected on a pair of nipples at once; but, if preferred, both chucks may be either trimmer-chucks or drill-chucks, and if both are drill-chucks the chuck on spindle B may carry the drill for the smaller hole in the nipple, as indicated in Fig. 12 of the drawings, while the other chuck may carry the larger drill for the unthreaded portion of the spoke to enter. It becomes necessary in this case, as is obvious, to extend one drill farther than the other, and this may be effected by turning the nuts f' f' on the spindles in the proper direction.

The sliding bar E'' has a bar F', similar to F, secured to one end thereof and extending in the same direction and in the same horizontal plane as the bar F. This bar F' is on the opposite side of the disk G, carrying

the nipples, and is provided with adjustable screws g and g' , extending through it in line with the spindles B and C on the opposite side of the disk G, which are for the purpose of bearing on the heads of the pair of nipples being operated upon by the trimming-cutters or the drills. The ends of the screws g and g' serve to hold the heads of the nipples firmly in place in their countersunk chambers or apertures and prevent them from turning. The cam-face on the wheel D'' is so shaped as to force the screws g and g' against the heads of the nipples immediately after the disk has shifted and before the trimmers or drills begin to act on the nipples, and said screws are moved from the heads after such operation is completed, when the disk G is again turned.

Coil-springs h and h' are connected with the sliding bars by pins projecting through slots in the guideways to retract the bars.

X is the driving-pulley on the driving-shaft. The disk G, carrying the nipples to be operated upon, is secured upon one end of a horizontal shaft G', which turns in bearings g'' and g''' in a bracket G'', secured to the front side of the frame A. The disk G is provided with a circular and concentric series of holes or chambers x x , &c., which extend through it near its periphery to receive and hold the nipples. Twenty holes are shown in the disk in the drawings, and these holes are just large enough to admit the shanks of the nipples, which before they are trimmed resemble common rivets and are countersunk slightly to receive the heads. Countersinking the holes x helps the screws g and g' to hold the nipples from turning. The nipples are inserted by hand in the lower part of the disk, which revolves in the direction of the arrows shown in Figs. 1 and 4. When a nipple reaches a point forty-five degrees above a horizontal plane extending through the axis of the shaft G', it is trimmed and centered by the knives in the trimming-chuck, as indicated in Fig. 11 of the drawings, after which it is carried step by step—a nipple being trimmed at each step by the same chuck—a distance of ninety degrees, when it is in position to be drilled by the drill in the chuck c'.

After the same nipple is carried by the disk to nearly its lowest point it is in position to be removed by the rod H, extending horizontally near the lower part of the frame. The said rod is in line with one of the nipples in the disk when the trimmer and drill are operating upon other nipples, and as the rod H, which may be termed a "pusher," is connected to and operated by the bar F it pushes a nipple out of the disk every time the spindles B and C are moved toward the disk.

The pusher H is reciprocated in an aperture in the end of a depending arm i, secured by a bolt to the web below the bearing g'' .

The end of the pusher farthest removed from the disk is secured adjustably in the lower end of an angular arm H', secured to the bar F.

The shaft G' is rotated intermittently by means of a ratchet-wheel J on the end opposite that carrying the disk G. The ratchet-wheel is provided with as many teeth as there are holes for nipples in the disk, the number in this case being twenty. The recesses in the periphery or the spaces between the teeth are shown square and are preferably made so in order that the disk may be held positively against movement in either direction during the trimming and drilling operations.

J' is the pawl for turning the ratchet-wheel J. Said pawl is connected at one end with a lever K, which is pivoted at its lower end to a projection l, extending from the angle of a bell-crank lever L, which is in turn pivoted at its angle to the frame A. One arm of the bell-crank lever extends horizontally to and below the ratchet-wheel, and its end is adapted to enter the recesses therein and forms the detent of said wheel, and the other arm extends vertically and is in position to be impinged by an adjustable screw k, passing through the lever K.

A coil-spring m connects the pawl J' with the detent-arm of the lever L and serves to draw them toward each other. Another coil-spring n is connected between the pawl J' and a bracket I, secured to the frame to operate on the pawl to turn the ratchet-wheel J. The pawl J' is moved in the opposite direction and the detent removed from the ratchet-wheel by means of a cam or, as shown in the drawings, a projection p, carrying a small roller p', extending from a sleeve on the driving-shaft D. As the said projection p revolves around the shaft the roller strikes the lever K, which carries the pawl J' forward to enter another recess in the ratchet-wheel. Just before the pawl reaches the end of its movement the screw k strikes the vertical arm of the bell-crank lever L, which throws the detent out of the recess in the wheel. As the roller p moves out of engagement with the lever K the spring n draws the pawl back, turning the ratchet-wheel and allowing the detent to fall into the next recess to hold the wheel against movement while other operations are performed on the nipples in the disk G.

The usual form of drill-chuck is employed. The trimming-chuck is flat, with a recess q in one side. r is the aperture to admit the nipple, r' is the centering bit or cutter to prepare the nipple for the drilling operation, and s is the trimming-cutter, which reduces the diameter of the end of the nipples, as shown in Fig. 11. Both of these cutters are provided with adjusting or set screws to hold them in place in the chuck.

I do not wish to be limited to the precise construction of the parts shown in the drawings, for it will be obvious that they may be changed in form without departing from my invention.

Having described my invention, what I claim as new, and desire to secure by Letters Patent, is—

1. In a nipple-finishing machine, the combination of a disk provided with a circular series of apertures to hold nipples, means to rotate the disk intermittently, a longitudinally-movable bar, a guideway for the bar, the driving-shaft, a cam-wheel on the driving-shaft to move the bar, a spindle adapted to be reciprocated in bearings by said bar, said spindle moving with and in the same direction as the bar, a tool on the end of the spindle to operate on the nipples, means to rotate the spindle, a second longitudinally-movable bar in a guideway, a cam on the driving-shaft to move the bar, and an arm carried by the said second bar and extending on the opposite side of the disk, as set forth.

2. In a nipple-finishing machine, the combination of a disk provided with a concentric series of apertures to hold the nipples, a shaft for the disk, a ratchet-wheel on the shaft, a pawl engaging the ratchet-wheel, the lever, K, connected to the pawl, a bell-crank lever pivoted to the frame and to the latter lever, one arm of the bell-crank lever serving as a detent for the ratchet-wheel, a contact carried on the lever, K, for engagement with the other arm of the bell-crank lever, a cam on the driving-shaft to engage the lever, K, a longitudinally-movable bar, a guideway for the bar, the driving-shaft, a cam-wheel on the driving-shaft to move the bar, a spindle adapted to be reciprocated in bearings by said bar, a chuck on the end of the spindle to hold a tool to operate upon the nipples, and a pulley on the spindle for rotating the same, as set forth.

3. In a nipple-finishing machine, the combination of a disk provided with a concentric series of apertures, a shaft for the disk, a ratchet-wheel on the shaft, a pawl engaging the ratchet-wheel, the lever, K, a bell-crank lever pivoted to the frame at its angle and provided with a projection connected to the lever, K, and a detent on one of its arms, an adjustable contact on the lever, K, to engage the other arm of the bell-crank lever, a roller carried on a projection extending from the driving-shaft to operate the lever, K, a longitudinally-movable bar, a guideway for the bar, the driving-shaft, a cam-wheel on the driving-shaft to move the bar, a spindle adapted to be reciprocated in bearings by said bar, a chuck on the end of the spindle to hold a tool to operate upon the nipples, and a pulley on the spindle for rotating the same, as set forth.

4. In a nipple-finishing machine, the combination of a disk provided with apertures to hold the nipples, means to rotate the disk intermittently, a reciprocating bar carrying a pair of parallel rotatable spindles parallel with the axis of the disk, said spindles being moved in the same direction as the bar, bearings for each of said spindles mounted on the frame of the machine for the spindles to slide and rotate in, a driving-shaft, a cam-wheel on the driving-shaft to move the said bar, cutters on the ends of the spindles to operate on

the nipples, and means to drive the spindles, as set forth.

5. In a nipple-finishing machine, the combination of a disk provided with apertures to hold the nipples, means to rotate the disk intermittently, a reciprocating bar carrying a pair of parallel rotatable spindles parallel with the axis of the disk, a driving-shaft, a cam-wheel on the driving-shaft to move the said bar, the spindles being moved with and in the same direction as the bar, cutters on the ends of the spindles to operate on the nipples, and means to drive the spindles, a second longitudinally-movable bar in a guideway, a cam-wheel on the driving-shaft to move the bar, and an arm carried by the said second bar and extending on the opposite side of the disk, as and for the purpose described.

6. In a nipple-finishing machine, the combination, of a disk provided with a circular series of apertures to hold the nipples, a shaft for the disk to turn in bearings, a ratchet-wheel on the shaft, a pawl engaging the ratchet-wheel, a cam on the driving-shaft to operate the pawl, a detent for the ratchet-wheel, a longitudinally-movable bar, a guideway for the bar, the driving-shaft, a cam-wheel on the driving-shaft to move the bar, a spindle adapted to be reciprocated in bearings, a bar connecting the spindle with the said longitudinally-movable bar, said connecting-bar being rigidly connected to the said movable bar, means for adjusting the spindle relatively to the said movable bar, a chuck on the end of the spindle to hold the tool to operate upon the nipples, and suitable means for driving the spindle, substantially as described and shown.

7. In a nipple-finishing machine, the combination of a disk provided with a concentric series of apertures, a shaft for the disk, a ratchet-wheel on the shaft, a pawl engaging the ratchet-wheel, a cam carried by the driving-shaft for operating the pawl, means to hold the nipple in the disk while it is operated upon, a longitudinally-movable bar, a guideway for the bar, the driving-shaft, a cam-wheel on the driving-shaft to move the bar in one direction, a spring to retract the bar, a spindle reciprocated in bearings by the said bar, said spindle being moved correspondingly with the bar, a chuck on the end of the spindle to hold a tool to operate upon the nipples, a pulley on the spindle for rotating the same, a longitudinally-movable rod held parallel with the axis of the disk in a bearing, and a connecting-bar between the latter and the longitudinally-movable bar, as and for the purpose described.

8. In a nipple-finishing machine, the combination with the frame and its projections and bearings, a driving-shaft carrying a driving-pulley and a pair of cam-wheels, a guideway on the frame, a pair of longitudinally-movable bars in the guideway to be operated by said cam-wheels, a disk provided with a concentric series of apertures for holding the

nipples, a ratchet-wheel on the shaft of the disk, a pawl and detent for the ratchet-wheel, a cam on a sleeve on the driving-shaft to operate the pawl and detent, a bar on one side 5 of the disk provided with screws to bear upon the heads of the nipples when they are operated upon, a pair of spindles having pulleys thereon and chucks to hold tools for operating on the nipples, said spindles being parallel with each other and on the opposite side 10 of the disk from the bar carrying the screws, an arm connected to the said spindles and adjustably mounted on one of the sliding bars, and a rod connected to the said arm and movable therewith to remove the nipples from the disk after they have been operated upon, as 15 set forth.

9. In a nipple-finishing machine, the combination with the frame and its projections 20 and bearings, a driving-shaft carrying a driving-pulley and a pair of cam-wheels, a guideway on the frame, a pair of longitudinally-movable bars in the guideway to be operated

by said cam-wheels, a disk provided with a 25 concentric series of apertures for holding the nipples, a ratchet-wheel on the shaft of the disk, a pawl and detent for the ratchet-wheel, a cam on a sleeve on the driving-shaft to operate the pawl and detent, a bar on one side 30 of the disk provided with screws to bear upon the heads of the nipples when they are operated upon, a pair of spindles having pulleys thereon and chucks to hold tools for operating on the nipples, said spindles being parallel 35 with each other and on the opposite side of the disk from the bar carrying the screws, and suitable means for removing the nipples from the disk successively after they have been operated upon, substantially as shown and described. 40

In testimony whereof I have hereunto signed my name.

ARTHUR J. MORSE. [L. S.]
